Atty.

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SIGNALING SYSTEM.

1,400,076.

Specification of Letters Patent. Patented Dec. 13, 1921.

Application filed December 16, 1919. Serial No. 345,380.

To all whom it may concern:

Be it known that I, CHARLES W. KECKLER, a citizen of the United States, residing at Newark, in the county of Essex and State 5 of New Jersey, have invented certain new and useful Improvements in Telephone Signaling Systems, of which the following is a full, clear, concise, and exact description.

This invention relates generally to signaling systems and more particularly to such 10 systems for use in connection with telephone systems.

The invention has for its object to provide in a telephone system, a means for signaling a station and automatically discontinuing that signal after a predetermined 15 time interval.

This is accomplished in accordance with this invention in its preferred form, by the 20 use of a combination of a delayed action relay which is energized by the operation of a key; another relay, which upon operation of the first relay, energizes, establishing other connections whereby it remains energized while the first relay releases; and a 25 third relay which, upon the operation of the second relay and the release of the first relay, operates to interrupt the signaling circuit and establish the talking circuit. A 30 second winding is provided on the second relay, by which the relay is adapted to be energized from a distant station whereby the third relay may be operated by the actuation of the first mentioned key, to open and close 35 the talking circuit without operating the signaling device.

This invention is especially adapted for use in connection with telephone systems such as loud speaker or train despatching 40 systems where attendants are at the various stations continuously. In such systems a signal such as a howl in the loud speaking receiver is desirable because it attracts the attention of the attendant before the conversation is begun, thus avoiding needless repetition.

The drawing shows schematically a loud speaking system having a central or master station and a number of substations. All 45 of the apparatus is located at the master station except that inclosed in dotted lines which comprises a substation. The invention in its preferred form is shown used for

the purpose of interrupting the signaling circuit and completing the talking circuit. 55

Only one substation, A, is shown in full, other stations being indicated and provided for as will hereinafter be described.

When the attendant at the master station wishes to communicate with station A, he 60 operates key a. Current then flows from grounded battery through buzzer 1, secondary induction coil windings 2 and 3, right normal contacts of relay 4, left contacts of key a to ground. This current is intermittent, due to the buzzer. Current also flows 65 from buzzer 1, through right outer contacts of key a, normal contacts of key T, receiver 8, condenser 7, right normal contacts of relay 4, left contacts of key a to ground. The howl produced in receiver 8 acts as a calling 70 signal to station A.

Simultaneously, current flows from grounded battery through normal contacts of relay 5, winding of relay 6, left contacts 75 of key a to ground. Slow acting relay 6 is thereby energized and operates after a certain time interval. Current then flows from grounded battery through alternate contacts of relay 6, left winding of relay 5, through 80 left contacts of key a to ground. Relay 5 operates, breaking the normal contacts and opening the circuit through relay winding 6 and the armature of relay 6 assumes its normal position. Relay 5 remains energized however, as current is supplied through the right alternate contact to the left winding of relay 5. Current then flows through 85 normal contacts of relay 6, left alternate contacts of relay 5, windings of relay 4, left contacts of key A to ground. Relay 4 operates, opening the buzzer circuit at the right 90 normal contacts of relay 4.

Upon operation of relay 4, current is supplied to the transmitter 9, through retardation coil 10, transmitter 9, alternate contacts of relay 4, left contacts of key a to ground. The path of the talking current oscillations is then from transmitter 9, alternate contact 95 relay 4, left contacts key a, ground, primary winding 12 of the induction coil, condenser 32, to transmitter 9.

The induced current from primary winding 12 flows from secondary winding 13 through left winding of mechanical amplifier 11 back to secondary winding 13. 105

Current to be amplified is supplied to the amplifier 11 through the primary windings 15 and 16, through the stationary electrodes and the granular carbon elements to the 5 movable central electrode of the amplifier 11, through the right winding of amplifier 11, retardation coil 14, right alternate contact of relay 4, left contact key *a* to ground. The central electrode of amplifier 11 vibrates under the influence exerted on the core 10 by the left winding of the amplifier and produces corresponding variations in primary windings 15 and 16.

Induced secondary current flows from 15 winding 2 through right alternate contacts of key *a*, normal contacts of key T, receiver 8, condenser 7, winding 3, to winding 2. Thus the communication at the transmitter 9 is heard at the receiver 8.

20 When the operator is talking at the master station key T of the substation is kept normal and the circuit of the transmitter 30 is open. However, when the operator at station A wishes to talk he operates key T and 25 key *a* is returned to its normal position.

Battery current is then fed through the right winding of relay 5, the upper left contacts of key T, to ground. Relay 5 remains 30 operated and relay 4 releases due to the opening of the circuit at left contacts of key *a*.

Battery current is supplied to transmitter 35 30 through retardation coil 21, transmitter 30, lower left contacts of key T, to ground.

35 The oscillations in the talking current follow the path, transmitter 30, lower left contacts key T, ground, primary winding 19, condenser 20 to transmitter 30. Secondary induced current oscillations follow the path 40 from secondary winding 18, through right winding of mechanical amplifier 17 to secondary winding 18.

As in the case of amplifier 11, amplifier 17 is supplied with current between primary 45 windings 23 and 24, through the outer electrodes, granular carbon elements and central vibrating electrode and left winding of amplifier 17, retardation coil 22, upper left contacts of key T to ground. Oscillations, 50 induced in the secondary windings 25 and 26 by the amplified alternations, flow through secondary 26, left contact of relay 4 and resistance 27, receiver 28, secondary 25, back to secondary 26. Thus the conversation at 55 transmitter 30 is reproduced at receiver 28.

If both keys, *a* and T, are operated at once, relay 4 is operated as before described and left contact of relay 4 is opened. The oscillations in receiver 28 are then reduced by 60 having to pass through high resistance 27. This prevents "singing" in the system which might be produced by the receiver 28 on the transmitter 9.

To produce a similar effect at station A, 65 resistance 31 is used, and the path of the

secondary induced current is changed as follows: Through secondary 2, resistance 31, alternate right contacts of key T, receiver 8, condenser 7, secondary 3 to secondary 2.

70 When a call originates at station A, key R is first operated. Battery current then flows through the buzzer 1, contacts of key R to ground, giving the master station the calling signal. Key T should then be operated and the identity of the calling station should be announced.

75 When the operator at the master station replies to station A, key *a* should be operated before key T is restored to normal. This is 80 desirable since, if key *a* is operated after key T, the howling signal is again transmitted to station A by the operation of key *a*. Relay 4 is operated immediately since 85 relay 5 is already actuated as before described.

Additional stations such as station B, etc., 90 may be provided which may be communicated with from the master station in the same manner as station A, by operating the 95 corresponding key *b*, etc.

Key M is used when it is desired to communicate with all stations simultaneously. Operating key M, as will be seen by referring to the drawing, performs the functions 95 of keys *a*, *b*, etc., by virtue of the fact that all the left spring contacts of keys *a*, *b*, etc., are strapped together and connected to right spring contact of key M.

The current is supplied to the system by 100 a common battery located at the master station. The positive pole of the battery is grounded and for uniformity the current has been described as flowing from negative pole to positive pole in the external circuits. 105

Condenser 29 is shunted across the armature and contact of buzzer 1 to prevent 110 sparking at the contact points.

What is claimed is:

1. A telephone system comprising a plurality of stations, a source of signaling current, means at one of said stations for selectively connecting said source to signal any one of said other stations, and a chain of 110 cyclically operating relays, consisting of a slow-acting relay, a second relay, energized upon the operation of said slow-acting relay, to release said slow acting relay, and a third relay, energized upon operation of the said second relay and release of the said slow- 115 acting relay, to disconnect said source of signaling current and establish a talking connection between first said station and said other station.

2. A telephone system comprising a plurality of stations, a source of signaling current, means at one of said stations for selectively connecting said source to signal any one of said other stations, and a chain of 120 cyclically operating electromagnetic relays, 125

consisting of a slow-acting relay, a second relay operative upon operation of said slow-acting relay, to release said slow-acting relay and establish connections whereby said 5 second relay remains operated, and a third relay, operative upon operation of the said second relay and the release of said slow-acting relay, to disconnect said source of

signaling current and establish a talking connection between first said station and said 10 other station.

In witness whereof, I hereunto subscribe my name this 10th day of December, A. D. 1919.

CHARLES W. KECKLER.
